1 Claim. (Cl. 246—33)

Our invention relates to track circuits and more specifically to a counter-voltage track circuit for positively controlling the signalling means.

In track circuit signalling systems in use at present, when the track section is occupied by a train, the train's wheels shunt the current away from the track relay, de-energizing the relay and causing the relay vane to drop to the downward position by gravity. When the train has left the track section, the relay becomes energized and functions to lift the vane. Operation of the vane of the track relay by gravity is unsatisfactory as friction, vibration, and stray electric currents can at times prevent gravity from operating the vane to the downward position. This causes the relay to function improperly and produces an incorrect signal. In addition, after the vane has dropped, gravity may not be sufficient to hold it down against the action of stray currents and vibration. This undesirable movement of the vane, and the relay contacts, tends to cause arcing across, and pitting of, these relay contacts.

Therefore it is an object of the present invention to augment the gravitational force, which now drops the vane, by adding an electro-magnetic force to positively operate the vane to the downward position, when the track section is occupied.

A further object of the invention is to secure the vane in its downward position against the action of stray currents and vibration, thus preventing arcing across the relay contacts and consequent pitting of these contacts.

Another object is to add an electro-magnetic force to the gravity force acting on the vane to speed up the operation of the vane in its downward travel.

We accomplish these and other objects by inserting in the track circuit a secondary voltage source which is smaller than, and of opposite polarity to, the primary source, and positioned at the same end of the track circuit as the relay.

For further comprehension of the invention and of the objects and advantages thereof, reference will be had to the following description, the accompanying drawing and to the appended claims in which the various novel features of the invention are more particularly set forth.

In the accompanying drawings forming a material part of this disclosure:

In the drawings, FIG. 1 is a combined wiring and schematic drawing of a track circuit embodying our invention.

FIG. 2 is a side view of a relay of the track circuit, together with its contacts, and with its vane in the upward position.

FIG. 3 is a view similar to that shown in FIG. 2 but with the vane in the downward position and with the contacts reversed.

FIG. 4 is a top view of the relay shown in FIGS. 2 and 3.

FIG. 5 is a modification of the invention shown in FIG. 1, showing an alternating current track circuit which may be used where direct current is used for train propulsion.

FIG. 6 is a further modification of the invention shown in FIG. 1, showing another type of alternating current track circuit which may be used where direct current is used for train propulsion.

FIG. 7 is another modification of the invention shown in FIG. 1 showing a direct current track circuit.

In the drawing and in the specification, in which like

2

numerals indicate similar elements (see FIG. 1), numeral 10 indicates an alternating current track circuit embodying the invention and comprised of a signal rail 11, return rail 12, a feed and equipment group 13, a relay end equipment group 14, and a conventional two element track relay 15.

The feed and equipment group 13 is comprised of a track transformer 16, resistor 17, and fuse 18, which are connected in a series arrangement to the rails at the feed end of the track circuit.

10 The relay end equipment group 14 is comprised of a transformer 19, a resistor 20, and a fuse 21, which are connected in a series arrangement with the relay 15, to the rails at the relay end of the track circuit. It should be noted here that the voltage of the track transformer 16 is 15 larger than the voltage of the transformer 19 and is of opposite polarity to it.

The conventional two element relay 15 is comprised of a frame 22 (partly shown) supporting a local electro-magnet core 23, whose coils are connected to the constant potential voltage source, a track electro-magnet core 24 whose coils are directly connected to a rail and the relay end equipment group 14, a rotatable vane 25, an upper contact 26, and a lower contact 27. The vane 25 is operated by the interaction of the two electro-magnet cores. When the vane is in an upward position upper contact 26 is closed and lower contact 27 is open; when the vane is in a downward position contact 26 is open and contact 27 is closed; thus a direct signal is produced, or an electric control is provided, whereby a signal can be given.

Now, referring back to the relative voltage settings of transformers 16 and 19—the purpose of these relative voltage settings is to permit the required amount of control current to pass through the circuit and function on the coils of the track electro-magnet 24 to raise the vane 25 and hold the vane raised (see FIG. 2), and so produce a signal when the track section (rails 11 and 12) is unoccupied. When the track section is occupied a shunt occurs on the rails and the control current from transformer 16 is shunted away from the relay thus preventing the control current from acting on the coils of the track electro-magnet 24. However the reverse control current from transformer 19 will now pass through the coils of the track electro-magnet 24 and being as the polarity of this current is opposite to that of the current produced by transformer 16, it functions on the coils of the track electro-magnet 24 to cause it to operate in the opposite direction to what would have been caused by the current from transformer 16, and to drive the vane 25 downward and hold it in a downward position (see FIG. 3), and thus produce a different signal.

It should be noted that the present invention requires two transformers in each track section. The number of transformers required can be reduced materially if the transformers used are of such a character that they are provided with at least two separate secondary windings. With this type equipment a transformer can function in one track circuit with one of its secondary windings as the track transformer 16 and with its other secondary winding as the transformer 19 in the adjacent track circuit.

Of course the two secondary windings referred to above must produce voltages of the proper magnitude and be installed to provide the proper polarity in the track circuit.

A modification of track circuit 10 is shown in FIG. 5. 65 Here a reactor 30 is positioned across the relay 15 and resistor 20. The purpose of the reactor is to shunt the direct current of the train motors away from the relay 15.

Another modification of track circuit 10 is shown in FIG. 6. This modification shows the feed and relay end equipment groups similar to those shown in FIG. 1. Here the relay is different and a balancing impedance is added in order to nullify the effects of the direct current on the

relay. This is accomplished by providing a relay 41, whose track winding is center tapped, in place of relay 15, and by adding a balancing impedance 42. The center tapped lead 43 of relay 41 is connected to relay end equipment group 14, one outside lead 44 of the relay is connected to the free end of the inductor portion 45 of the balancing impedance, and the other outside lead 46 of the relay is connected to the free end of the resistor portion 47 of the balancing impedance. The joined ends 48 of the resistor and inductor go to a rail.

By this construction the alternating current travels through the resistor 47 and causes the relay 41 to function while the direct current divides between the resistor 47 and inductor 45 and has no effect on the relay.

It is possible to provide other modifications of the circuits hereinabove shown and described in which direct current train propulsion and alternating current track circuits are used wherein resistors, capacitors, inductors, and transformers are connected to the relay or relay equipment group to nullify and/or counteract the effect of the direct current on the relay.

In the modification shown in FIG. 7, direct current is used throughout the track circuit. Here the feed end equipment group 50 is comprised of a direct current source 51, such as a battery, rectifier, or motor-generator set, a resistor 52 and a fuse 53. These elements are connected in series across the track rails at the feed end of the track circuit. The relay end equipment group 54 is comprised of a direct current source 55, a resistor 56 and a fuse 57, connected in series to the relay 58 and the track rails at the relay end of the track circuit. The relay 58, in this circuit, is of the biased neutral type. The voltage of source 55 is less than that of source 51 and is of opposite polarity to it. Thus when the track section is unoccupied the resultant voltage of the circuit is in a direction to keep the relay vane in the upward position, and when a train is on the track rails (shunting out source 51) the circuit voltage is in the opposite direction and holds the relay vane in the downward position against the action of any stray currents or vibration.

Although we have shown the invention exemplified by several different types of circuits it should be understood

that other groupings of electrical units not shown or described herein may be used to form circuits different from those described herein but which circuits will embody the basic principles and ideas herein set forth. Therefore, we do not wish to limit ourselves to the precise circuits herein disclosed, and we therefore reserve the rights to all changes and modifications of the invention coming within the scope of the invention as defined in any or all of the appended claims.

Having thus described our invention, what we claim as new and desire to secure by United States Letters Patent is:

A track circuit comprised of a pair of running rails, a feed end source of alternating current, a relay end source of alternating current, a two element alternating current relay with a center tapped track winding and a balancing impedance, said feed end source being secured across the running rails and said relay end source of current, relay and impedance being connected in series to a rail, and said feed end source being of opposite polarity to and greater magnitude than the relay end source of current, and said impedance being inserted in the relay end of the track circuit with its free ends connected to the outside leads of the track winding and with its joined end connected to one of the rails, whereby when the running rails are unoccupied the resultant current from the sources causes the relay to function in one way, and when the running rails are occupied by a train the current from the feed end source is shunted away from the relay and the current from the relay end source operates the relay in another way.
